OIL BURNING EQUIPMENT AND CONTROL-
LING MECHANISM THEREFORTheodore Nagel, Brooklyn, and Harold D. Bliss,
South Salem, N. Y.; said Bliss assignor to said
Nagel

Application September 11, 1942, Serial No. 457,934

4 Claims. (Cl. 158—36)

1

This invention is directed to oil burning systems and has for one of its objects the provision of an oil burning system which, while it may be controlled manually or semi-automatically is preferably controlled entirely automatically, wherein the practical maximum fuel range is very materially increased as compared with existing automatically controlled systems.

In marine service, for example, the fuel range requirements for ships at sea approximate 8 to 1. Prior to my invention the practical maximum fuel range of oil burning systems for marine service at sea, where oil pressure and flow are varied under automatic combustion control, is about 2½ to 1. In oil burning systems with constant pressure, variable capacity oil burners, having oil recirculation systems with automatic combustion control, the practical maximum fuel range approximates 5 to 1. For the wider fuel range demand in marine service at sea, the two systems above referred to require the manual turning off and relighting of burners.

The present invention provides an oil burning system which meets the demands above referred to, in that we provide for a fully automatically controlled system covering a fuel demand of any practical wide range, as 8 to 1, for example, for ships at sea, with fire in all furnaces, and without changing nozzle sizes, without manually relighting burners previously turned off and without removing burners when they are turned off.

It is to be understood, of course, that our improved system is adapted for other than marine work, the marine service having been mentioned purely by way of illustration as a certificate of need.

Broadly speaking, our invention provides an oil burning system wherein a multiple number of oil burner nozzles, constituting a nest, are placed at each furnace firing entrance, through which fuel and air are injected. These nozzles are so arranged and controlled that one nozzle will continuously deliver oil and remain lighted so long as the furnace is in service, and function as a torch for lighting the other nozzles as they are placed in service.

The burner nozzles of the nest are of different capacities and there is but one nozzle in service at any time additional to the torch nozzle, the nozzle in operation at any instant depending upon the steam demand on the system.

In the accompanying drawing:

Fig. 1 is a diagrammatic view of an embodiment of our invention;

Fig. 2 is a detail of part of the master control;

2

Fig. 3 is an enlarged sectional elevational view of a control valve assembly employed in the system illustrated in Fig. 1; and

Fig. 4 is a section on the line 4—4 of Fig. 3.

5 I, II, III, IV and V designate a plurality of pressure atomizing nozzles disposed at the one firing opening 4 of a furnace. The number of furnace firing openings and the number of nozzles composing each nest of nozzles may be varied as desired to meet the demands of any installation. For clarity of description and illustration only one furnace firing opening has been shown with a nest of five nozzles at this opening, the nozzles increasing in capacity in the order I, II, III, IV, V. 10 The nozzles are so disposed relatively to each other and to the furnace firing opening that the spread of the diverging stream of ignited atomized oil from each nozzle approximates the diameter of the firing opening so that one of the 15 nozzles which is always burning as long as the furnace is in service will function as a torch in lighting the other nozzles when steam demand requires that they be set in operation.

12 designates a steam main from the steam generating system. 14 designates a master control comprising a pressure tube 16 which communicates with the steam main 12 through line 18. The oil supply line is designated 20 and extends into an oil pressure regulator or rotary 20 valve mechanism 22. This oil pressure regulator 22 controls the supplying of oil to nozzles II, III, IV and V, lines from the oil pressure regulator to the nozzles being designated II', III', IV' and V', respectively. The line leading to nozzle I is 25 designated I' and by-passes the regulator 22. The line I' is equipped with pressure reducing valve 24.

30 Nozzle I is equipped with manually operated combined oil and purge valve 26. Each of the 35 nozzles II, III, IV and V is equipped with a combined oil and purge valve 28, each of these valves being electrically operated, the solenoids therefore being shown at 30. Purge line 32 is common to all of the oil valves and as will be seen from 40 the drawing is connected to the steam main 12. As the oil valve at each nozzle is closed the purge line 32 to that nozzle will be opened to purge the nozzle.

45 Combustion air to the nozzle is supplied by 50 electrically driven constant speed blower 34. The quantity of combustion air being supplied at any given instant is controlled by damper 36. This damper, as will be brought out presently, is automatically controlled from the master control 14 so that although the nozzles II, III, IV and V

are of different capacities, damper 36 will be set correctly in accordance with the nozzle in operation at any instant.

In addition to the pressure tube 16, master control 14 comprises reversible electric motor 38, the circuits of which are controlled by movable contacts 40 and 42 in turn controlled by the pressure tube 16, the contact 40 being adapted under certain conditions to bridge fixed contacts 44 while contact 42 is adapted under other conditions to bridge fixed contacts 46. It will be seen from the drawing that the contacts 44 when bridged are adapted to close a circuit to the motor 38 to drive the same in one direction, while the contacts 46 when bridged are adapted to close a circuit to the motor 38 to drive the same in the opposite direction.

Mounted above the motor 38 is a jack shaft 50 geared to the motor by reduction gear train 52. A cam 54 is mounted on this jack shaft and cooperates with a follower bar or follower rod 56 pivoted intermediate its ends, as shown at 58. Connected to the free end of the follower bar or rod 56 are two springs 60 and 62. The lower end of the spring 60 is anchored while the upper end of the spring 62 is connected by a cable 64, passing over an idler roller 66, to the free end of the pressure tube 16. The function of this master control is to start the motor 38 in one direction or the other, depending upon a few ounces rise or fall of steam pressure in the pressure tube 16 upon increase or decrease in steam demand, thereby through various instrumentalities which will be later referred to automatically selecting the nozzle of the proper capacity to be set into operation in accordance with the mentioned variation in steam demand and to open the circuit of the motor 38 when the steam being generated meets the steam demand. It will be apparent from an inspection of the drawing that upon a few ounces variation in the steam pressure in the system the position of the free end of the pressure tube 16 is altered to close contacts 44 or 46, as the case may be. As the jack shaft 50 is rotated, due to this operation of the motor, there is a change in the relative tension of the springs 60 and 62 through pivoting of the follower rod 56 and when the forces of steam pressure and spring tension have become balanced the motor circuit automatically opens and movement of jack shaft 50 ceases. It will be seen, therefore, that the master control operates in a series of steps for a given pressure increment above or below normal steam pressure.

It will be seen from Figs. 3 and 4 that the pressure regulator 22 comprises a hollow rotor 68 mounted within casing 70. This rotor is equipped with a sprocket wheel 72 driven through chain 74 and sprocket 76 on the jack shaft 50 of the master control. Within the rotor 68 is a cylindrical stator 78 which is in constant communication with the oil supply line 20. The casing 70 heretofore referred to of the oil pressure regulator is provided interiorly with circumferentially extending ports 80, 82, 84, 86, with which the oil lines II', III', IV' and V' are in constant communication.

Rotor 68 is provided in its periphery with ports 88, 90, 92 and 94. These ports, lengthwise of the rotor, are spaced according to the spacing of the circumferential ports 80, 82, 84 and 86 in the casing 70. The stator 78 is provided with ports 96, 98, 100 and 102. The spacing of these ports also lengthwise of the stator corresponds to the

spacing in the same direction of the ports 80, 88, etc., in the shell 70 and rotor 68.

The ports 88, 90, 92 and 94 circumferentially of the rotor 68 and the ports 96, 98, 100 and 102 circumferentially of the stator 78 are so spaced that rotation of the rotor 68 will bring the ports 88 and 96 into register with each other so that oil from the line 20 may flow to the line II' of nozzle II, the other ports of the rotor 68 and stator 78 being at that moment out of register with each other so that lines III', IV' and V' are not being supplied with oil at that moment. Further rotation of the rotor 68 will bring ports 98 and 90 of the stator 78 and rotor 68 into register to permit oil to flow through the line III' to the nozzle III, this movement of the rotor at the same time moving port 88 out of register with port 96 to shut off the oil to the line II'. In other words, this arrangement is such that as the oil to the nozzle of one capacity is shut off the oil to the next nozzle of a different capacity to be operated is turned on.

As already pointed out, each of the oil valves of the nozzles II, III, IV and V is equipped with a solenoid 30 and it is not only necessary that the solenoid to one of these oil valves have its circuit closed in order to open the oil valve but at the same time the oil pressure regulator 22 should function to open the oil line to that particular valve. For example, it is necessary that the solenoid 30 for the oil valve of the nozzle II have its circuit closed at the same instant that the port 88 in the rotor 68 is brought into register with the ports 96 in the stator 78.

The circuits of the various solenoids for the burner oil valves are controlled by a tip or nozzle selector switch 104 which is driven off the jack shaft 50 of the master control. This tip selector switch comprises four fixed contacts 106, 108, 110 and 112 adapted to be engaged by a switch arm 114 which is driven from the jack shaft 50. In addition the tip selector switch comprises pressure tubes 116, 118, 120 and 122 connected, respectively, to the oil lines II', III', IV' and V' leading to the oil valve of nozzles II, III, IV and V, respectively, and these pressure tubes are adapted to bridge fixed contacts 124, 126, 128 and 130 connected, respectively, to fixed contacts 106, 108, 110 and 112 and to the solenoids 30 of the oil valves for the nozzles II, III, IV and V, respectively.

As was pointed out above, inasmuch as the nozzles II, III, IV and V are of different capacities, it is necessary that the combustion air to the nozzles be controlled so as to ensure the correct amount of combustion air to whichever nozzle is in operation at any instant, and inasmuch as the blower 34 which supplies this combustion air is a constant speed blower, it is necessary to vary the setting of the damper 36 in accordance with the nozzle capacity. Accordingly the shaft of the jack shaft 50 of the master control is equipped, for instance, with an arm 132, and cable 134 passes from this arm and is connected to counterweighted arm 138 of the damper 36.

In operation and assuming that burner I is turned on and has been ignited and is operating at 125 pounds oil pressure: It will be understood that the pressure reducing valve 24 in the oil line to nozzle I is set for 125 pounds oil pressure and that its setting is not changed. Under these conditions combustion air is being supplied to nozzle I by natural draft.

Assuming now that there is a demand for a larger quantity of steam: Under these condi-

tions there will be a slight change in pressure in the pressure tube 16 of the master control, this tube, as above pointed out, being connected to the steam main 12. Consequently the free end of the tube will move to cause the contact 42 to bridge fixed contacts 46 and close a circuit to the motor 38 of the master control.

The circuit of the motor 38 now being closed, the rotor 68 of the oil pressure regulator 22 will be rotated to bring the port 88 thereof into register with the port 96 of the stator 78 to open the oil line II' leading to the oil valve of nozzle II. At the same time the arm 114 of the tip selector switch 104 will engage the fixed contact 106 of that switch and the pressure tube 116 which is connected to the oil line II' will bridge the contacts 124 so that a circuit is now closed to the solenoid 30 of the oil valve for nozzle II and this valve will be opened, the purge line 32 to that nozzle being closed as the oil valve moves to open position. Oil will now, therefore, be supplied to nozzle II. At this same time also, due to the starting up of the motor 38, the damper 36 will be moved into position to permit air from the blower 34 to flow to nozzle II. As explained above, the five nozzles of the nest are so relatively disposed that nozzle I, which is always on fire when the equipment is in service, will function as a torch to light the other nozzles. Consequently operation of nozzle II will now have been established or initiated. Nozzle II is of larger capacity than nozzle I. The oil pressure in the line II', which to start with was at 125 pounds, begins to increase. So long as the demand for steam continues to increase so that there is a slight pressure drop in the tube 16 of the master control, the circuit of the motor 38 will remain closed, the damper 36 will continue to move toward open position and the rotor 68 will continue to rotate until the oil pressure to the nozzle II is built up to 250 pounds. Building up of the oil pressure in line II' from 125 pounds to 250 pounds will be understood from an inspection of Figs. 3 and 4. Assuming that rotor 68 is rotating because of a demand for more steam, it is apparent that 68 will rotate from a position where line II' is closed to a position where port 96 in stator 78 and port 88 in the rotor are in full register. In other words, port area gradually increases from zero to maximum. If at that time rotor 68 still continues to rotate, port area will gradually be reduced to zero again and further rotation of 68, because steam demand is still unsatisfied will move rotor 68 to bring the next set of ports, which are for line III' into gradual register. In other words, with ports 96 and 88 in full register, maximum oil pressure of 250 pounds has been reached.

If the demand for steam is not met when the oil pressure to nozzle II has built up to 250 pounds, the motor 38 will rotate to bring the arm 114 on to fixed contact 108 and at that time the rotor 68 will have rotated sufficiently far to bring the ports 96 and 88 out of register with each other and the ports 90 and 98 into register with each other. As soon as the ports 88 and 96 move out of register with each other, nozzle II will be shut off, the circuit to the valve of nozzle II opening at the pressure tube 116 which it is to be remembered is connected to the oil line II' of nozzle II. As the port 90 of the rotor 68 begins to uncover the port 98 of the stator 78, pressure will be built up in the tube 118 of the tip selector control switch mechanism and a circuit is closed to the solenoid of the oil valve for nozzle III, the nozzle of the next higher capacity, 75

and the same cycle of operation is gone through at this nozzle, as explained in connection with nozzle II. As this next larger capacity nozzle goes on oil, the oil pressure drops to 125 pounds and nozzle II automatically goes off oil, after which the oil pressure begins to build up again to 250 pounds and if the steam demand is still not satisfied higher capacity nozzles IV and V will go on successively, the preceding nozzle shutting off each time as explained in connection with nozzles II and III.

With nozzles I and V in operation, the system is steaming at capacity.

It will be appreciated that should the demand for steam be satisfied at any point between the operation of nozzle II and nozzle V, the circuit of the motor 38 will open and further operation of the oil pressure regulator 22, damper 36 and tip selector control switch 104 will cease.

It has already been explained that as the oil valve at each nozzle shuts off the purge line 32 to the nozzle of that burner is automatically opened so as to purge the nozzle.

For a continuing decrease in demand for steam the cycle above described is reversed. Under these conditions there will be a few ounces rise in pressure in the tube 16 of the master control so that fixed contacts 44 will be bridged to close the circuit to the motor 38 to rotate the same in a direction opposite to that first described.

Let us assume that nozzle I and highest capacity nozzle V are in operation on this decrease in steam demand: Under these conditions the operation of the motor 38 will effect rotation of the rotor 68 gradually to move the port 94 out of register with port 102 in stator 78, decreasing the oil pressure in the line V'. When this oil pressure has reached 125 pounds the circuit for the solenoid for the oil valve of nozzle V will be opened at the contacts 130 and arm 114 will swing out of contact with contact 112 which is in the circuit of this same solenoid.

Consequently nozzle V will be shut off and the succeeding lesser capacity nozzle IV turned on oil due to further rotation of the rotor 68 and assuming that the demand for steam on the system continues to decrease. As nozzle IV goes on the oil pressure is at maximum, namely, 250 pounds, and as the rotor 68 continues to move

40 this pressure will drop until nozzle IV goes off and nozzle III comes on. This cycle is repeated until the operation again becomes stabilized to satisfy the steam demand.

It will be seen from all of the foregoing that this equipment provides for maintenance of substantially constant steam pressure through the medium of a nest of atomizing nozzles of different capacities located at the firing opening of a furnace, the nozzles of the nest being automatically controlled by a master control.

It will be seen also that so far as the nozzles of the nest are concerned, one nozzle is always in operation so long as the equipment is in use in order that it may function as a torch for the other nozzles when the demand for steam requires their operation, it being understood, of course, aside from the constantly operating nozzle but one nozzle of the nest is in operation at any instant.

It is to be understood that changes may be made in the details of construction and arrangement of parts herein illustrated and described within the purview of our invention.

What we claim is:

1. An oil burning system for generating steam,

comprising in combination a plurality of pressure atomizing nozzles of different capacities at a firing opening of a furnace, the operation of said nozzles being controlled by the steam demand on a boiler being fired by the furnace, an oil valve for each nozzle, a solenoid for each valve, an oil pressure regulator for regulating the oil pressure to each nozzle, a master control comprising a reversible electric motor, said master control being under the direct control of the steam pressure in the system, whereby upon increasing steam demand on the system the circuit to the solenoid for the valve of one nozzle will be opened to interrupt the operation of said nozzle and simultaneously the circuit of the solenoid for the oil valve for the nozzle of the next larger capacity will be closed to open said valve, and simultaneously said oil pressure regulator will be operated, whereby operation of the said larger capacity nozzle at reduced oil pressure will be initiated.

2. An oil burning system for generating steam, said system comprising in combination a plurality of pressure atomizing nozzles of different capacities at a firing opening of a furnace, an electric valve for each nozzle, a master control for said nozzles under the direct control of the steam being generated, said master control including a reversible electric motor the circuit of which is controlled by steam pressure, a nozzle selector comprising a switch arm driven by said motor, contact mechanism cooperating with said switch arm for opening and closing the circuits of said electric valves in the order as determined by the said reversible motor and the steam demand on the system, and means for supplying oil and combustion air to the nozzles in fixed oil-air ratio but in varying quantities dependent upon the capacity of the nozzle being operated at any given instant, said last mentioned means being controlled by the said master control.

3. An oil burning system for generating steam, comprising in combination a plurality of pres-

sure atomizing nozzles of different capacities at a firing opening of a furnace, means for supplying oil and air to said nozzles, an electrically operated oil valve for each nozzle, switch mechanism for said valves, and a master control comprising a reversible electric motor under the direct control of the steam pressure in the system operable to operate said switch mechanism to initiate the operation of said nozzles in the ascending order of their capacities on increasing steam demand on one direction of rotation of said motor and to reverse this cycle on decreasing steam demand upon rotation of said motor in the opposite direction, said oil supplying means comprising an oil pressure regulator driven by said reversible motor and provided with a port for each nozzle, whereby the quantity of oil supplied to the system will vary in accordance with the nozzle in operation at any instant, said air supply means comprising a damper controlled by said motor whereby the air supplied to the system will vary in accordance with the capacity of the nozzle in operation.

4. An oil burning system comprising in combination a plurality of pressure atomizing nozzles of different capacities at a firing opening of a furnace, a master control therefor including a reversible motor, an oil pressure regulator comprising a ported rotor driven by said motor for controlling the pressure of the oil being delivered to the nozzles, switch mechanism controlled by the steam pressure being generated for controlling the circuit of said motor, an electric oil valve for each nozzle, selective switch mechanism driven by said electric motor for selecting the nozzle valve to be operated at any instant depending upon the setting of said ported rotor and the steam demand on the system, thereby to maintain the steam pressure on the system substantially constant.
